LOOPEP PILE FABRIC

Edward A. Smith, Haworth, N. J., assignor to Collins & Aikman Corporation, Philadelphia, Pa., a corporation of Delaware

Application November 10, 1953, Serial No. 27,540

Term of patent 3½ years

(Cl. D92—1)

Fig. 1

Fig. 3

To all whom it may concern:

Be it known that I, Edward A. Smith, a citizen of the United States of America, residing at Haworth, in the county of Bergen and State of New Jersey, have invented a new, original, and ornamental Design for a Looped Pile Fabric, of which the following is a specification, reference being had to the accompanying drawing, forming a part hereof, wherein:

Fig. 1 comprises a flat plan view of a looped pile fabric embodying my new design, drawn to an enlarged scale.

Fig. 2 is a sectional view of the looped pile fabric in elevation looking in the direction of the arrows II—II.

Fig. 3 is a sectional view of the looped pile fabric in elevation looking in the direction of the arrows III—III.

I claim:

The ornamental design for a looped pile fabric, as shown.
